UNITED STATES PATENT OFFICE.

FREDERICK S. BOSWORTH, OF PROVIDENCE, RHODE ISLAND, ASSIGNOR TO
THE WEYBOSSET MILLS, OF SAME PLACE.

DESIGN FOR FANCY CASSIMERES.

Specification forming part of Design No. **8,675**, dated October 5, 1875; application filed September 18, 1875.
[Term of Patent 7 years.]

To all whom it may concern:

Be it known that I, FREDERICK SNOW BOSWORTH, of the city and county of Providence, in the State of Rhode Island, have invented a new and Improved Design for Fancy Cassimeres; and I do hereby declare that the following specification, taken in connection with the drawings making a part of the same, is a full, clear, and exact description thereof.

The distinctive peculiarity which characterizes the design for fancy woven cassimeres, hereafter described, consists in the novel composition of the broad stripe A, running lengthwise of the fabric, ornamented with a Grecian chain of a peculiar pattern, and also in the effect produced by the arrangement in a pattern of such peculiarly-composed stripes A, with narrow separating-stripes B. The Grecian chain upon the stripe A is composed of short sections of basket-weaving, *a*, arranged in two lines alternately with each other, and connected by cross-bars *b*. The ornamental portion of the stripe A is placed upon a ground of plain weaving, and narrow

stripes B, of a common pattern, are arranged lengthwise of the fabric alternately with the broad stripes A.

Stripes of any other common pattern may be substituted for the stripes B to mark the boundaries of the broad stripes A, and the effect will be the same; or the narrow stripes may be omitted altogether, and the Grecian chain or stripes A be separated from each other by simple stripes of plain weaving.

The design may be represented in any variety or combination of colors that may be preferred for bringing out the best effect of the pattern.

What I claim as my invention, and desire to secure by Letters Patent, is—

The design for fancy cassimeres, substantially as described, and shown in the drawings.

FREDERICK SNOW BOSWORTH.
